UNITED STATES PATENT OFFICE.

EDWARD SIDNEY BARNSTABLE, OF NOKOMIS, ILLINOIS, ASSIGNOR OF ONE-HALF TO D. E. AYLWARD AND ONE-HALF TO JOHN W. BUSKER, BOTH OF LIVINGSTON, ILLINOIS.

MINER'S CARBIDE-LAMP HOLDER.

Application filed September 19, 1921. Serial No. 501,801.

To all whom it may concern:

Be it known that I, EDWARD SIDNEY BARNSTABLE, a citizen of the United States, residing at Nokomis, county of Montgomery, 5 and State of Illinois, have invented certain new and useful Improvements in Miners' Carbide-Lamp Holders, of which the following is a specification.

This invention relates to miners' carbide 10 lamp holders and more particularly to an improved device for holding the lamp in firm and rigid position on the miner's cap.

One of the objects of the invention is to obviate the use of the customary hook and 15 at the same time hold the lamp so the loose swinging motion of the lamp will not occur.

Other objects of the invention will appear upon consideration of the following detail 20 description and accompanying drawings in which like reference numerals indicate corresponding parts throughout the several views.

In the drawings:

Fig. 1 is a perspective view of the improved holder.

25 Fig. 2 is an edge elevation of the same.

Fig. 3 is a back view.

Fig. 4 is a top edge view.

Fig. 5 is a side elevation of a lamp illustrating the objectionable hook.

30 Fig. 6 is a side elevation of a similar lamp with the hook displaced and showing the lamp attached to my improved holder.

Fig. 7 is a perspective view of the cap shield or plate.

35 Fig. 8 is a similar view showing the holder attached to the cap shield or plate.

Referring to the drawings by numerals, the lamp 10 is of the conventional type usually equipped with a hook 11. In using 40 the present improvement the hook 11 is detached from the lamp and will be discarded. The conventional type of cap shield or plate 12 is mounted on the miner's cap and is employed with this device. This cap shield 45 consists of a plate fixed to the front of the cap and has a lower angular portion 13 conforming to the visor of the cap, and a top flange 14 extending over a portion of the top of the cap. The longitudinal edges of 50 the shield are turned upon themselves to reinforce the shield as shown in Figs. 7 and 8.

The holder consists of central body plate

16 substantially rectangular in form and less in width than the width of the shield 12 and provided at its upper end with a 55 backwardly extending flange 17 adapted to overlie the top flange 14 of the shield 12. Two pairs of oppositely extending retaining arms 18 and 19 are integrally formed with the body plate 16 and extend from the edges 60 thereof near the upper and lower ends of the said body plate 16. These retaining arms 18 and 19 are equipped at their ends with spring clips 20 which are adapted to be 65 clipped around the edges of the shield 12.

It will be noted that the shield is provided with a lip at the corner from which the top flange 14 extends thus forming an abutment member 21 adapted to engage the uppermost pair of retaining arms 18 to prevent upward movement of the holder. The flange 17 engaged with the flange 14 of the shield prevents downward movement of the holder.

Resilient lamp engaging bands 22 are 70 integrally formed with and extend from the intermediate portion of the body plate 16 and are curved to fit the lamp body 10 and have sufficient resilience to firmly grasp the lamp. The terminals of the bands 22 are 75 turned outwardly as indicated at 23 to facilitate insertion of the lamp.

What I claim is:

1. A miner's carbide lamp holder, in combination with a shield fixed to the miner's cap, a body plate having retaining arms adapted to engage the shield and hold the plate thereto, the said shield having an abutment member engaged with certain of 85 said retaining arms to prevent upward movement of the body plate on the shield, means to prevent downward movement of said body plate, and lamp engaging means carried by said body plate.

2. A miner's lamp holder, in combination with a shield fixed to the miner's cap, and having a top flange extending over a portion 90 of the top of the cap, a body plate having a flange at one end adapted to overlie said top flange to prevent downward movement 95 of said body plate, retaining arms carried by said body plate and engaged with said shield, means engaged with the uppermost 100 retaining arms to prevent upward move-

ment of said body plate, and lamp engaging means carried by said body plate.

3. A miner's lamp holder, in combination with a shield fixed to a miner's cap, and provided with a top flange and an outwardly projecting abutment member, a body plate having an upper flange adapted to engage

said top flange, upper and lower retaining arms carried by said body plate, the uppermost arms being engaged with said abutment member, and lamp engaging means carried by said body plate. ¹⁰

In testimony whereof I affix my signature.
EDWARD SIDNEY BARNSTABLE.
